W. G. JONES.

BINDER LOCK,

APPLICATION FILED MAR. 28, 1913.

1,070,691.

Patented Aug. 19, 1913.

UNITED STATES PATENT OFFICE.

WILLIAM GIFFORD JONES, OF CHICAGO, ILLINOIS, ASSIGNOR OF ONE-HALF TO HARRY SLOPER JONES, OF CHICAGO, ILLINOIS.

BINDER-LOCK.

1,070,691.

Specification of Letters Patent.

Patented Aug. 19, 1913.

Application filed March 28, 1913. Serial No. 757,362.

To all whom it may concern:

Be it known that I, WILLIAM GIFFORD JONES, a citizen of the United States, residing at Chicago, in the county of Cook and 5 State of Illinois, have invented a new and useful Improvement in Binder-Locks, of which the following is a specification.

My invention relates particularly to loose-leaf binder-locks of the type set forth in my 10 Patent No. 816,915.

My primary object is to provide a lock of the type referred to of improved construction and operation.

The invention is illustrated in its preferred embodiment in the accompanying drawing, in which—

Figure 1 represents a broken plan view of a binder-frame and lock co-acting therewith shown separated therefrom; Fig. 2, a 20 broken longitudinal vertical section showing the lock connected with the binder; Fig. 3, an enlarged vertical sectional view of the improved lock with the bolt in the locking position; Fig. 4, an enlarged broken 25 transverse section taken as indicated at line 4 of Fig. 2; Fig. 5, an enlarged rear end view of the bolt-actuating key-barrel employed; and Fig. 6, an enlarged front elevational view of the bolt.

The binder in connection with which the invention is, for convenience, illustrated, comprises a back A equipped with a screw-rod A', which is provided at one end with an angled key-receiving shank 1, by means of 35 which the rod may be actuated; a pair of clamping members B, B' transversely slidable upon the back A and equipped with the usual extensible binding-posts B²; wedge-shaped followers B³ having screw connection with the rod A' and slidable connection with the oblique guides 2 with which the clamping members are equipped; and flexible members B⁴ connected with the members B³ and with the clamping members and 40 serving in the operation of closing the clamping members in a well known manner.

The shank portion 1 of the screw-rod A' is housed beneath a bridge member 3 having portions 3^a which serve as transverse 50 guides for the binder-frame. That is, the bridge portions 3^a are separated from the inner surface of the back member A by spaces 4, as shown in Fig. 4, which admit the inturned flanges 5 of the clamping members B, B'. The bridge portions 3^a are sepa-

rated by a slot or space 6, beneath which the back A is provided with a longitudinal recess or concavity 6^a intercepted near its inner end by a bolt socket or cavity 7. The lock C comprises a casing 8 which is adapted 60 to slide within the lock-receiving cavity of the binder-frame afforded by the slot 6 and concavity 6^a, said casing comprising an approximately cylindrical lower portion 8^a and an upward extension 8^b of general rectangular form, but with slightly convergent sides, thus having the form of a keystone; a vertically disposed bolt 9 adapted to work in a vertical chamber 9^a with which the casing 8 is provided at its rear portion, the chamber 70 9^a being open at its lower end; a rotatable key-barrel 10 contained in the bore with which the lower portion 8^a of the casing is provided, said bore intercepting the vertical bore 9^a; and a series of barrel-locking plungers 11 adapted to be moved during the insertion of the key to release the barrel in the usual manner.

The barrel is provided with the usual longitudinal key-slot 12 which is provided with 80 a ledge 12^a adapted to support the balls associated with the barrel-locking plungers 11. The rear end of the barrel 10 is equipped with an eccentrically mounted pin 13 which engages a transverse slot 13^a in the front 85 surface of the vertically disposed bolt 9.

The portion 8^b of the lock-casing serves to house the upper sections 11^a of the tumblers or barrel-locking plungers. When the key 14 is inserted, the plunger sections will 90 separate on the line 11^b, allowing the barrel to be turned to retract the bolt. When this action occurs, it will be noted that the lower sections of the plungers will be locked within the bore which contains the barrel 10, so 95 that the key will be locked within the barrel and will serve as a means for withdrawing the lock-casing from the binder-frame.

The barrel 10 is provided near its front end with a circumferential groove 15 which 100 intercepts the key-slot 12 and is adapted to engage an internal lug 16 with which the lock-casing is equipped near its front end. The key-barrel may be entered by alining the slot 12 with the lug 16, and after partial rotation the key-barrel is locked in position by the lug 16, as will be evident from Fig. 4.

It will be understood that after the binder has been adjusted to clamp the leaves 17, 110

the lock may be inserted and secured by turning the key to the withdrawing position, after which the key may be withdrawn, leaving the lock secured in place. The removal 5 of the lock may be effected in the manner suggested above, after which a separate key may be employed for actuating the screw-rod A'. When the lock-casing is in position, it is additionally secured by lateral shoulders 18 with which the portion 8^a of the lock-casing is provided, while the portion 8^b of the lock-casing projects through the slot or space 6. After the bolt is retracted by means of the key 14, the lock 15 may be withdrawn by longitudinal movement. To prevent the bolt from turning in its guide, it is preferred to employ a transverse pin 19 which engages a slot 19^a with which the bolt is provided in its upper portion. 20

From the foregoing description it will be understood that the improved lock is of simplified construction, and that its parts may be readily separated at will to facilitate inspection or repair. Also, the bolt 9 is adapted to have secure engagement with the socket 7, so that there is no danger of these parts wearing to such extent as to jeopardize the efficiency of the lock. 25

30 The foregoing detailed description has been given for clearness of understanding, and no undue limitation should be understood therefrom.

What I regard as new and desire to secure by Letters Patent is— 35

1. The combination with an expandible binder-frame equipped with actuating means and provided with a lock-chamber having a bolt-socket associated therewith, of a removable lock comprising a lock-casing, a key-barrel extending thereinto, barrel-locking means connected with said lock-casing, a bolt in the rear portion of the lock-casing disposed at right angles to said barrel, and 45 an eccentric pin carried by the inner end of said barrel and engaging a slot in said bolt.

2. The combination with an extensible binder-frame provided with actuating means, including a screw-rod having a key- 50 engaging shank and a bridge-piece carried by the binder-frame and provided with a

slot, of a removable lock comprising a lock-casing having lateral shoulders engaging the lower surface of said bridge-piece and having an upward extension extending through 55 said slot, a bolt in said casing adapted to engage a socket with which the binder-frame is equipped, a key-barrel in said lock-casing, and actuating means for the bolt carried by said key-barrel. 60

3. The combination with a binder-frame comprising a back, transversely-slidble clamping members mounted thereon, and actuating means for said clamping members, including a screw-rod, of a member carried 65 by said back and spaced a short distance therefrom, said member provided with a longitudinal slot and said back provided with a concavity disposed beneath said slot, and a lock comprising a lock-casing having 70 its lower portion fitting in said concavity and having also an upward extension projecting through said slot, said lock-casing having lateral shoulders disposed beneath the member carried by said back, a bolt in 75 the lock-casing engaging a socket in said back, and a key-barrel in said lock-casing equipped with means for actuating said bolt.

4. A lock for the purpose set forth, comprising a lock-casing having its rear portion provided with a vertical bore and its front portion provided with a horizontal bore, a bolt in said vertical bore having its front portion provided with a slot, and a 85 key-barrel in said horizontal bore having its rear end equipped with an eccentric pin engaging said slot. 80

5. A lock for the purpose set forth, comprising a lock-casing having its rear portion provided with a vertical bore and its lower front portion provided with a horizontal bore, a bolt in said vertical bore, and a key-barrel in said horizontal bore equipped with means for actuating said 95 bolt, said horizontal bore having an internal stud engaging a circumferential groove with which said key-barrel is provided. 90
